UNITED STATES PATENT OFFICE.

FRANZ SCHMIDT, OF MILWAUKEE, WISCONSIN, ASSIGNOR TO ALLIS-CHALMERS
MANUFACTURING COMPANY, OF MILWAUKEE, WISCONSIN, A CORPORATION
OF DELAWARE.

GUIDE-VANE.

1,248,168.

Specification of Letters Patent. Patented Nov. 27, 1917.

Application filed May 22, 1915. Serial No. 30,236.

To all whom it may concern:

Be it known that FRANZ SCHMIDT, a citizen of the United States, residing at Milwaukee, in the county of Milwaukee and 5 State of Wisconsin, has invented a certain new and useful Improvement in Guide-Vanes, of which the following is a specification.

This invention relates to improvements in 10 the construction of turbine gate mechanisms and especially to improvements in guide vane construction.

An object of the invention is to provide a 15 guide vane for motive fluid, which is simple in construction and efficient in operation. Several of the more specific objects of the invention may be enumerated as follows:

To provide a guide vane in which the cost 20 of construction is reduced to a minimum by eliminating the necessity of grinding the guiding surfaces of the vane.

To provide a guide vane in which the warping which often occurs when constructing guide vanes of cast metal, such as steel, 25 is eliminated.

To provide a guide vane of minimum weight, thereby facilitating the handling of the vane both during the machining operations and during installation of the same.

To provide a relatively flexible guide vane 30 which will permit tighter closing of the gate than is permitted with the use of cast steel and iron guide vanes.

To provide a guide vane which will be 35 stronger and not so readily broken by impact with other objects, as are the cast metal guide vanes at present in use.

To provide an efficient guide vane which 40 may be readily constructed of sheet material, either in several sections or in one piece.

To provide simple and efficient means for bracing a sheet metal guide vane.

To provide various improved details of 45 construction specific to guide vanes having sheet metal guiding portions.

A clear conception of several embodiments of the invention may be had by referring to the drawing accompanying and forming a part of this specification in which 50 like reference characters designate the same or similar parts in the various views.

Figure 1 is a plan view of a guide vane applicable to outside gate riggings.

Fig. 2 is an end view of the guide vane 55 disclosed in Fig. 1.

Fig. 3 is a fragmentary elevation of a guide vane and its pivot shaft, applicable to inside gate riggings.

Fig. 4 is a view looking at one end of the 60 guide vane disclosed in Fig. 3.

Fig. 5 is a view looking at the opposite end of the guide vane disclosed in Fig. 3.

Hydraulic turbine gate riggings of either 65 the inside or the outside type generally comprise a circular series of movable guide vanes which are adjustable each about its own pivot, to vary the size of the opening leading to the turbine. It has been customary in the prior art to form these movable guide vanes of either cast iron, cast 70 steel, or other cast metal. The present invention contemplates forming the movable guide vanes of sheet metal, preferably sheet steel, in order to eliminate various difficulties encountered with the prior devices, 75 and also to produce a more efficient vane at a lower cost of construction.

Referring specifically to Figs. 1 and 2, the 80 guide vane comprises essentially a plane guiding sheet 1, a curved guiding sheet 2, and an actuating element or stem 3 located between the sheets. The guide vane disclosed in these figures is especially applicable to an outside gate rigging, the actuating mechanism being applied to the projecting end of the stem 3 adjacent the bearing portion 5. The sheets 1, 2, if formed of 85 separate pieces as disclosed, are united by fusion of metal, as by welding, at the joint 6 and have their opposite edges united by 90 means of rivets 7. It should however be understood that it is not necessary to utilize the welded joint 6 or rivets 7 as disclosed, as any other effective form of fastening might be substituted in order to produce a union 95 between the sheets 1, 2. The stem 3 has an intermediate flattened portion 8 provided with substantially plane surfaces which engage adjacent surfaces of the sheets 1, 2.

The stem 3 which is preferably forged of 100 steel, has substantially equal cross-sectional areas throughout its length and is secured to the plane surfaces of the portion 8 by means of rivets 9 or any other suitable fastening. Cylindrical bearing portions 4, 5, are formed 105 on the shaft 3 adjacent the portion 8, and normally coact with suitable bearings in the stationary frame of the turbine.

If necessary, the sheets 1, 2, may be stiffened by the use of bracing elements either 110

in the form of stay-plates 10 or of stay-bolts 11. While both of these forms of bracing elements have been shown in the form of guide vane disclosed in Figs. 1 and 2, such disclosure is merely illustrative and either one or the other form of bracing element alone may be used. Each of the stay-plates 10 is preferably secured directly to the guiding sheet 2 on the bulged side of the vane, 10 and has its opposite end engaging a notch or recess in the stem 3. As disclosed, some of the rivets 9 which secure the sheets 1, 2, to the stem 3 are also utilized to fasten the plates 10 to the stem 3 and to the adjacent 15 sheet 1. By arranging the stay-plates 10 as disclosed, an effective truss for supporting the sheet 2 is provided.

Referring specifically to Figs. 3, 4 and 5, the guide vane comprises essentially a plane 20 guiding sheet 12, a curved guiding sheet 13, and a pair of end portions 16, 17, one at each end of the sheets 12, 13. The guide vane disclosed in these figures is especially applicable to inside gate riggings, the actuating 25 mechanism being applied to the vane at a pin normally fitted in the socket 21 formed in the end portion 17. If the sheets 12, 13, are formed as separate pieces as disclosed, they are preferably united by fusion of 30 metal, as by welding, at the joint 20, and have their opposite edges united by means of rivets 19. It should however be understood that it is not necessary to utilize a welded joint 20 or rivets 19, as disclosed, as 35 any other effective form of fastening might be substituted in order to produce a union between the two sheets. The end portion 16 has surfaces which engage surfaces of the sheets 12, 13, and is secured to these sheets 40 by means of rivets 18 or any other suitable fastening. The end portion 17 has surfaces which engage adjacent surfaces of the sheets 12, 13, and is secured to these sheets by means of rivets 18. The portions 16, 17, 45 have aligned bores within which are fitted the concentric bearing bushings 15. The bushings 15 normally coat with a stationary shaft 14 which forms the pivot about which the vane is movable. If necessary, the 50 guide vane disclosed in Figs. 4 and 5 may also be provided with bracing elements, as disclosed in Fig. 2.

As sheet metal ordinarily has fairly smooth surfaces, the use of this material in 55 the construction of guide vanes eliminates necessity of grinding the guiding surfaces, which is ordinarily necessary in the construction of cast metal vanes. The warping which often occurs when cast metal vanes 60 cool, such warping generally being due to defective formation of the mold or to unequal shrinkage of the metal, is also eliminated by the use of sheet metal in constructing the vane. As the characteristics of sheet 65 metal especially its relatively high tensile

strength as compared with that of cast metal, permit the use of relatively thin material, the weight of the guide vane may be materially reduced by forming it of sheet metal, thereby facilitating handling of the 70 vane both during the machining operations and during installation of the same.

As the relatively thin guiding portions of a vane formed of sheet metal may be readily distorted a slight amount, the use of such 75 vanes will permit tighter closing of the gates than is at present permitted with the use of cast steel and iron guide vanes. The fact that the sheet material is more flexible than the cast material, also prevents the sheet 80 material vane from breaking, due to impact with other objects. While both constructions disclosed in the drawings show the guiding portions 1, 2, 12, 13, as formed of separate sheets united by welded and riveted joints, it should be understood that the 85 vane may be formed of a single plate of sheet material.

It should be understood that it is not desired to be limited to the exact details of 90 construction shown and described, for obvious modifications will occur to a person skilled in the art.

It is claimed and desired to secure by Letters Patent,—

1. As an article of manufacture, a movable guide vane having guiding portions formed of sheet metal, means secured to said sheet metal portions and having surface contact therewith, and a pivot associated 100 with said means.

2. As an article of manufacture, a movable guide vane having guiding portions formed of sheet metal, and a stem upon 105 which said guide vane is movable, said stem being rigidly secured to at least one of said guiding portions and having surface contact therewith.

3. As an article of manufacture, a movable guide vane having guiding portions 110 formed of sheet metal, said portions being united by fusion of metal, means adjacent the ends of said vane for movably supporting the same, and means affording surface contact with said guiding portions for rigidly securing said supporting means thereto.

4. As an article of manufacture, a movable guide vane having guiding portions, one of said portions comprising a substantially plane sheet of metal and another of 120 said portions comprising a curved sheet of metal, said sheets being secured to each other by fusion of metal, means secured to said sheet metal portions and having surface contact therewith, and a pivot associated 125 with said means.

5. As an article of manufacture, a guide vane having sheet metal guiding portions, a stem engaging at least one of said portions, and a bracing element having an end secured 130

to one of said guiding portions and engaging said stem with its opposite end.

6. As an article of manufacture, a guide vane having two sheet metal guiding portions, a stem engaging one of said portions and having a recess therein adjacent said portion, and a bracing element having an end secured to the other of said guiding portions and engaging said stem at said recess 10 with its opposite end.

7. As an article of manufacture, a stem having a cylindrical end portion and having a flattened portion adjacent said end portion, said portions having substantially equal cross-sectional areas, and a sheet metal 15 guiding portion secured to said stem at said flattened portion.

In testimony whereof, the signature of the inventor is affixed hereto.

FRANZ SCHMIDT.
